US0D1077441S

(12) **United States Design Patent** (10) **Patent No.:** **US D1,077,441 S**
(45) **Date of Patent:** **** Jun. 3, 2025**

(54) **SOLE**

(71) Applicant: **DECATHLON**, Villeneuve d'Ascq (FR)

(72) Inventor: **Rémi Amoretti**, Villeneuve d'Ascq (FR)

(73) Assignee: **DECATHLON**, Villeneuve d'Ascq (FR)

(**) Term: **15 Years**

(21) Appl. No.: **29/917,161**

(22) Filed: **Nov. 17, 2023**

(30) **Foreign Application Priority Data**

May 22, 2023 (EM) 015022323

(51) **LOC (15) Cl.** **02-04**

(52) **U.S. Cl.**

USPC **D2/956; D2/951**
